UNITED STATES PATENT OFFICE.

JULES HIPPOLYTE CORTHESY, OF LONDON, ENGLAND, ASSIGNOR OF ONE-HALF TO
SAVERIO THOMAS STEPHEN CASTELLI, OF LONDON, ENGLAND.

MEANS TO GENERATE GAS FROM COAL AND ANALOGOUS SUBSTANCES.

1,360,503.

Specification of Letters Patent. Patented Nov. 30, 1920.

Application filed May 10, 1919. Serial No. 296,270.

To all whom it may concern:

Be it known that I, JULES HIPPOLYTE CORTHESY, a citizen of the Republic of Switzerland, residing at 50 Thornhill 5 Houses, Barnsbury, London, England, have invented new and useful Improvements in Means to Generate Gas from Coal and Analogous Substances, of which the following is a specification.

- 10 This invention relates to apparatus for the generation of gas from coal or like fuel in a pulverulent condition and wherein the fuel is subjected to a whirling or like motion.
- 15 Apparatus of this class has heretofore been proposed for producing gas designed for immediate combustion, either for the treatment of materials mixed with the fuel or for other heating purposes, a whirling motion of the fuel being produced by means of an air jet or jets.

The object of this invention is to provide apparatus of the kind above referred to wherein gas can be generated which can be 25 used for lighting purposes and to this end the invention may be said to consist mainly in the utilization of a portion of the gas generated for maintaining in motion or suspension the fuel which is to be subjected to 30 the distilling action without the employment of atmospheric air the oxygen of which would tend to render the gas unstable.

In a suitable construction for carrying out 35 this invention I arrange generating chambers for two qualities of gas and for this purpose I provide a cylindrical case in the upper portion of which is arranged a cone and around the base of which part is an annular opening which communicates with a 40 chamber or space below the said cone. The fuel is first introduced into the generating chamber, hereinafter referred to as the distilling chamber, above the cone, where it is subjected to the vortex action of a current 45 of a portion of the gas just previously generated in the said chamber and distilled therein, the coke or residue of the distillation then passing into the lower chamber where it is acted upon by an air current 50 which again imparts motion to it and wherein in gas of a different nature is produced. Steam may be introduced into this lower chamber so that water-gas is generated, the gas passing up through the interior of the cone and being led off to any point for 55 combustion and during its passage heating the

upper chamber and superheating the gas current above referred to, or independent means may be employed for effecting such superheating. Such a degree of superheating may be imparted to the gas current in the distilling chamber by said independent means as to enable the complete distillation of the fuel introduced into it to be effected.

This invention will be readily understood 65 by reference to the accompanying drawing, in which:—

Figure 1 is a vertical central section of a generator constructed according to my present invention, and

Fig. 2 is a plan of the same.
Fig. 3 is a section on the line 3—3, Fig. 1.
Fig. 4 is a section on the line 4—4, Fig. 3.
Fig. 5 is a sectional view illustrating a detail.

Fig. 6 is a view illustrating a modification of the arrangement shown in Fig. 4, and

Figs. 7 and 8 are sectional views illustrating modifications of the generator.

Fig. 9 is a sectional view similar to Fig. 80 1 illustrating a further modification of my invention.

Figs. 10 and 11 are sections on the lines 11—11 and 12—12, of Fig. 9, respectively; and,

Fig. 12 is a sectional view of still another modification.

In the arrangement of this invention shown in Figs. 1 to 4 the casing *a* of the generator is divided into two chambers *b*, *c* the division between which chambers is in the form of a hollow cone *d*, and the communication between the two chambers is in the form of an annular opening *e* around the base of the cone and between the latter 95 and a lining ring *f* of the casing.

The chamber *c* has at the lower part a grate *g* upon which a fire is lighted for starting the generator, and an ash-pit *g'* below the said grate provided with an opening which will be closed when the generator is in operation.

The pulverized fuel to be distilled is introduced into the distilling chamber *b* by means of any suitable feeding arrangement, 105 such, for instance, as that indicated in Fig. 1 and which consists of a serrated or grooved feed wheel or roller *h* rotating in a cylindrical chamber *h'* in the lower end of a feed pipe or hopper *h''*. The gas generated in 110 the chamber *c* passes up through an outlet pipe *i* connected to the small end of the

cone d , and the gas generated in the distilling chamber b escapes through an outlet passage i^1 formed by a casing i^2 surrounding the pipe i .

- 5 Upon the wall of the casing a is a pipe j which opens tangentially into the chamber b and which also communicates with the passage i^1 through which gas from the chamber b escapes, a fan k being arranged in 10 this pipe to withdraw a portion of the gas passing through the pipe i^1 and return it to the chamber b in order to produce a vortex action therein to distribute the fuel in a well-known manner.

- 15 Under the heat which is imparted to the apparatus initially by lighting a fire on the grate g , the fuel in the chamber b will be subjected to the action of distillation, the gas given off escaping through the passage i^1 ; 20 and as a portion of this gas, which is at a high temperature, is returned into the said chamber b by the fan k , the distillation will be accelerated.

- The fuel residues resulting from the distillation in the chamber b pass through the 25 annular opening e around the base of the cone into the chamber c , wherein the said residues are subjected to a vortex action by means of an air current introduced tangentially through a pipe l and wherein, owing to the heat within the said chamber, the complete decomposition of the fuel will be effected. The gas generated in the chamber e passes up through the cone d to the outlet pipe i . m is a supplementary grid or 30 grate advantageously formed of inclined radial bars m^1 for confining the vortex action to the upper part of the chamber c and prevent it interfering with the fire on the grate g .

- As gravitation and concentration may cause the fuel to travel in close proximity to the walls of the chambers b and c and to adhere thereto, I may arrange around the 45 cylindrical walls of the chamber projections or baffles such as m^2 , Fig. 5, which serve to cause a disturbance in the fuel particles coming in contact with the walls and thereby maintain them in suspension.

- 50 It will be understood that the louver like arrangement of the radial bars m^1 shown in Fig. 4 is not essential for instance, bars of V or triangular section can be employed as shown in Fig. 6.

- 55 As illustrated in Fig. 1 the pipes j and l open into the chambers b , c the full depth of the latter so that the respective currents of gas and air directed thereby act upon the whole of the fuel passing through the said 60 chamber at any moment. It will also be noticed in the said figures that the said currents for producing a vortex action in the chambers b and c are arranged in the same direction.

- 65 As the temperature in the chamber c ,

wherein actual combustion takes place, is higher than the temperature in the chamber b , I advantageously provide for imparting some of the heat of the gases passing up through the pipe i to the gases which are drawn from the passage i^1 and reintroduced into the chamber b , this additional heat assisting in the distillation of the fuel in the said chamber. As shown in the drawing, the pipe or flue i is provided with a lateral extension n on one side and which forms an inner wall of the passage j , and into this extension projects a baffle or deflector n^1 which will compel the gases passing through the pipe i to pass in contact with the wall n and thereby heat the latter, which heat in its turn will be imparted to the gases drawn through the pipe j to be reintroduced into the chamber b .

In starting the apparatus a fire must be lighted upon the grate g to heat up the apparatus to the desired temperature as previously stated, and when this temperature has been obtained it will be maintained by the combustion within the respective chambers. The ashes resulting from the combustion of the fuel ultimately fall through the supplementary grate m on to the grate g and through the latter into the ash-pit g^1 .

It is to be understood that the gas produced in the chamber b is produced at such a temperature that distillation only takes place so that a gas which can be used for illuminating purposes is given off, whereas the gas which is generated in the chamber c contains a considerably less proportion of hydrocarbons and is therefore better adapted for heating and power purposes.

In some cases the air supply may be limited and steam may be introduced into the chamber c with the air through a pipe o arranged within the pipe l , in which case producer gas will be generated.

If it is not desired to ultimately obtain gases of two distinct kinds, the two kinds of gas which are generated can be mixed together, in which case the cone d is arranged to open at the upper end of the chamber c directly into a pipe i^3 into which the gas from the said chamber c also enters in a manner which will be clearly understood by reference to Fig. 7.

In order to facilitate the escape of the illuminating gases a steam jet may be provided in the pipe i^1 as indicated at p in Fig. 8. A similar device can also be employed in connection with the pipe i to facilitate the escape of the gases from the chamber c . Or in place of a steam jet any suitable mechanical device can be used.

Fig. 8 also shows an arrangement wherein in the gas introduced into the chamber b through the pipe j is gas drawn from the chamber c by a fan k or other appliance for effecting the introduction.

In the arrangement of my invention shown in Fig. 1 it is assumed that the walls are lined with some non-conducting material; in order, however, to utilize the heat to the best advantage I, in some cases, arrange a jacket through which the air or gas, introduced into the respective chambers for producing the vortex action therein, will be caused to pass before entering the distilling and combustion chambers. Such an arrangement is shown in Figs. 9 to 10. In these figures r indicates a jacket surrounding the chamber b and to which jacket the pipe j extending from the passage i^1 is connected so that the gas drawn by the fan k from the passage i^1 enters the said jacket. When I employ this jacket I advantageously form a series of tangential openings r^1 around the wall of the chamber b , as clearly indicated in Fig. 10, for the passage of the gas to form the vortex. The chamber c is also surrounded by a jacket s , and the pipe t through which the air is introduced into this jacket is connected with a jacket s^1 which surrounds the passage i^1 so that the heat of the gas passing through the said passage i^1 will be transmitted through the wall thereof to the air which passes down through the jacket s^1 into the chamber c . In this case also the heated air will enter the chamber c through a series of tangential openings s^2 as indicated in Fig. 11. Furthermore, the pipe o through which the steam enters the chamber c can be extended up through the furnace and into the pipe i as indicated in the said Fig. 9, so that the steam can be superheated.

In this modification the base of the cone d , instead of being carried nearly to the wall of the chamber b as in Fig. 1, is made smaller and the space between the said base and the wall is provided with a series of louver plates t^1 similar to the plates m^1 , Fig. 4, to prevent mixing of the gases generated in the two chambers. The grate g is also dispensed with, the fire for starting the apparatus being made on the grid m .

To obviate the necessity for employing an exterior independent boiler for the generation of steam when steam is required for making producer gas, I advantageously arrange a boiler within the apparatus itself and which will be heated by the heat due to the combustion which takes place therein. Such an arrangement is illustrated in Fig. 12 wherein u indicates the boiler which is located in the chamber c , water being introduced into the said boiler through the pipe u^1 and the steam escaping therefrom through the pipe u^2 and being conducted, by a pipe u^3 , to a nozzle v within the air admission pipe v^1 . In this modification also I have dispensed with the use of a circular or vortex action for maintaining the fuel in mo-

tion, and rely on the gas of the chamber b operated upon by a fan w for producing the requisite current. This fan w , is preferably of the centrifugal type and draws a portion of the gas generated in the chamber b through the pipe x , and returns it through the pipe x^1 , which passes through the chamber c to the upper part of the chamber b where the said gas comes into contact with the fuel dropping through the opening x^2 , the gas during its passage through the chamber c being superheated. In a similar way the air introduced into the chamber c through the pipe v^1 , will maintain the requisite current for the movement of the fuel in said chamber. y is a partition between the chambers b and c with inclined openings which while allowing the passage of the fuel prevent the mixing of the gases from the two chambers.

Claims.

1. An apparatus for the generation of gas from fuel in pulverulent condition comprising a distilling chamber, means for feeding pulverulent fuel into said chamber, an outlet for the gas generated in said chamber, a passage directly connecting the outlet and chamber, and a fan for causing a portion of the gas entering the outlet to be returned through the passage directly to said chamber for agitating said fuel. 85

2. An apparatus as claimed in claim 1 in which the chamber has a curved wall and the passage opens tangentially into said chamber to cause the returned gas to whirl the pulverulent fuel. 95

3. An apparatus as claimed in claim 1 including a lower chamber, arranged beneath the distilling chamber, into which the fuel treated in the distilling chamber falls by gravity. 100

4. An apparatus as claimed in claim 1 including a lower chamber, arranged beneath the distilling chamber, into which the fuel treated in the distilling chamber falls by gravity, and a hollow cone arranged in the distilling chamber and having its base communicating with the lower chamber, and a gas outlet for the lower chamber connected to the apex of the cone. 110

5. An apparatus for the generation of gas from fuel in pulverulent condition, comprising a first distilling chamber, means for feeding pulverulent fuel into said chamber, an outlet for the gas generated in said chamber, a passage placing the chamber and outlet in direct communication, means for causing a portion of the gas entering the outlet to be directly returned through the passage to said chamber for agitating said fuel, a second distilling chamber adapted to receive the fuel after it has been treated in the first chamber, and means for conducting gas generated in the second

chamber through said first chamber to cause heat exchange between the gases.

6. An apparatus as claimed in claim 5, having means for admitting air to the second distilling chamber.

7. An apparatus as claimed in claim 5 having means for admitting steam and air to the second distilling chamber.

8. An apparatus as claimed in claim 5, 10 in which the first distilling chamber has a curved wall and the passage, returning a portion of the gas generated to the first chamber, opens tangentially into said first chamber to cause the returned gas to whirl 15 the pulverulent fuel.

9. An apparatus for generating gas from pulverulent fuel comprising upper and lower distilling chambers in communication with each other, means for feeding pulverulent fuel into the upper chamber, a gas 20 outlet extending upwardly from the upper chamber, a passage placing said outlet in communication with one side of said upper

chamber, means for causing a portion of the gas entering said outlet to be returned to 25 the upper chamber through said passage, a hollow cone located in the upper chamber and having one of its ends communicating with the lower chamber, a gas outlet for the lower chamber connected to said cone, and 30 means for admitting steam to the lower chamber.

10. In an apparatus for generating gas from pulverulent fuel, a gas generating chamber, means for introducing pulverulent fuel into said chamber, a fire-box located beneath said chamber, means for introducing a gaseous current under pressure into said chamber for sweeping the pulverulent fuel through the chamber, and a grid 35 arranged between the fire-box and chamber and having inclined bars for preventing the gaseous current from disturbing the fire in the fire-box.

JULES HIPPOLYTE CORTHEZY
